US00D987984S

(12) United States Design Patent (10) Patent No.: US D987,984 S
Feng (45) Date of Patent: * Jun. 6, 2023

(54) PILL CASE

(71) Applicant: GUANGZHOU WENYI
COMMUNICATION EQUIPMENT
CO., LTD, Guangzhou (CN)

(72) Inventor: YouRu Feng, Guangzhou (CN)

(73) Assignee: GUANGZHOU WENYI
COMMUNICATION EQUIPMENT
CO., LTD, Guangzhou (CN)

() Term: 15 Years

(21) Appl. No.: 29/773,494

(22) Filed: Mar. 10, 2021

(51) LOC (14) Cl. 03-01

(52) U.S. Cl.

USPC D3/203.3
